(57) **CLAIM**

The ornamental design for a remote control as shown and described.

DESCRIPTION

FIG. 1 is a front, top, and right perspective view of a remote control showing our new design;

FIG. 2 a rear, bottom, and left perspective view thereof;

FIG. 3 is a front view thereof;

FIG. 4 is a rear view thereof;

FIG. 5 is a left side view thereof;

FIG. 6 is a right side view thereof; and

FIG. 7 is a top view thereof; and,

FIG. 8 is a bottom view thereof.

The even spaced broken lines and unshaded regions shown in the drawings depict portions of the article that form no part of the claimed design.
